JEAN BROADHURST, OF NEW YORK, N. Y., ASSIGNOR OF ONE-HALF TO STANLEY J.
STANLEY, OF NEW YORK, N. Y.

PROCESS OF MAKING STOPPERS

Application filed January 12, 1928. Serial No. 246,285.

This invention relates to a process of making stoppers having particular reference to stoppers for use in connection with test tubes, bottles or other containers used particularly 5 in laboratories and hospitals.

In common practice, use is generally made of raw cotton as a stopper or plug for test tubes, bottles and other containers, such stoppers or plugs usually being fitted to the containers at the time of making. In so making these stoppers, a quantity of raw cotton appropriate to the size of tube or bottle is obtained and is twisted or rolled by hand to such size as to properly fit within the mouth 10 or neck of the container. It is very obvious that this practice has a great many objections, chief among which is that the stopper must be of approximately the same size as the mouth or opening of the tube or container 15 with which it is used requiring the exercise of skill in selecting the requisite amount of material in making and shaping the stopper. Should too great a quantity be used, the stopper will be of such size as to necessitate discarding it entirely or to involve remaking 20 and reshaping it, or to compress too tightly or compactly the material thereof when being forced into the tube or bottle, whereby the latter is too completely sealed to allow the 25 free passage of air, steam or vapor necessary in many of the routine procedures for which such plugs or stoppers are used, such as the cultivation of bacteria and the heating and sterilizing of containers and culture 30 media. On the other hand, should the quantity of material taken be too small, a stopper of insufficient size will result and will drop into the bottle or tube. Furthermore, the time required in this cumbersome practice 35 renders the same highly objectionable.

It is the primary object of the present invention to provide a stopper of such character as to be adaptable to tubes or bottle mouths of various sizes, which will effectively seal 40 the container with which it is used against the ingress of bacteria, dust or other foreign bodies, yet which will possess a degree of perviousness such as will permit air, steam or vapors to pass therethrough. Stoppers possessing these characteristics are adapted par-

ticularly for use in connection with bottles, flasks, tubes or the like wherein there are contained liquids, chemicals, culture media or other matter of like nature for making dilutions or culture media for growing bacteria 55 or as containers of pathological or other diagnostic specimens.

A further object is to provide plugs or stoppers of such character or degree of perviousness that when heated they will retain 60 their position in the tubes during the sterilizing process and so insure sterility of the liquid or media in the tubes.

A further object is to provide a stopper capable of withstanding flaming without detracting from the efficiency of the stopper or affecting the degree of porosity of the latter.

A still further object is to provide a stopper and process by means of which the stoppers may be produced by extremely simple 70 operations, at low cost and at great saving of material, and wherein the stoppers so produced retain their shape and effectiveness notwithstanding repeated or continuous usage.

In the drawings forming part of this specification:

Fig. 1 is a side elevation of a blank from which the stoppers of my invention may be made,

Fig. 2 is a side elevation of one of the blanks 80 prior to the treatment in accordance with my invention,

Fig. 3 is an end view of the blank shown in Fig. 2,

Fig. 4 is a longitudinal section taken 85 through blanks shown in Fig. 2 and illustrating the first stop in my improved process,

Fig. 5 is a sectional view illustrating a form or mold for carrying out the shaping process,

Fig. 6 is a side elevation showing the plug or stopper at the completion of the process, and

Fig. 7 is a fragmentary sectional view showing the application of my improved stopper to the neck of a bottle or test tube. 95

In the accomplishment of the objects set forth, use is made of paper, wood, or fiber pulp formed or rolled substantially cylindrical in shape, the fibers of which may be matted in the several layers and may be disposed 100

parallel or otherwise to the axis of the roll. The blank thus formed is cut transversely entirely through at such places as will produce a plug or stopper of the desired length, such 5 plugs being represented at 8 in the drawings. In their initial form as thus cut, the plugs are truly cylindrical, and in order that the stoppers be adaptable to bottle necks or tubes within a varied, though limited range 10 of sizes, the plugs are shaped to a taper toward one end. This is accomplished by subjecting one end of the cylindrical fiber stopper or blank to moisture. The application of moisture to the stopper end may be accomplished by subjecting the same to a body of liquid, permitting a drop or more of liquid to engage the stopper end, or the process may be effectively carried out by subjecting the stopper end to a jet or spray of steam, vapor 15 or moist air, while, again, the reduced end of a mold for shaping the stopper may be moistened in any preferred manner so that the stopper end will be subjected to moisture upon being applied to the form.

20 25 The blank with its end thus moistened is placed or slightly forced into a form 9 of substantially frusto-conical shape and remains so positioned until properly shaped. The drying of such shaped plugs may be carried out naturally, or, if desired, more rapid drying may be effected by subjecting the forms containing the stoppers to the action of heat or a blast of warm air, or by applying warm air to the shaped but incompletely 30 35 dried stoppers. The drawings illustrate the application of moisture to the plug and by dipping or touching the plug end to a liquid contained in a pan or trays 10, but it will be understood that the moistening process 40 45 may be carried out in other ways as above suggested. The mold 9 shown in the drawings is of conventional form, and it will be understood that apparatus for shaping the stoppers may take forms other than that described and illustrated.

50 55 The moistening of one end of the blank saturates all fibers immediately adjacent to that end, and pressure brought about by compressing the end as by applying the mold or form, slightly mats or compacts the moistened portion, the compression, however, is insufficient to destroy porosity of the moistened portion, nor does it seal or render the treated end thereof impervious.

60 65 70 When dry, the stopper or plug will be found to retain the substantially frusto-conical shape, as the moistening and drying operations have permitted the plug end to become "set", and the plug thus becomes permanently shaped in accordance with the form to which it has been subjected.

In practice, it will be found that plugs or stoppers constructed in accordance with the foregoing description will prove highly effective in the associations with which its uses

are adapted. The plugs are extremely easy to handle or manipulate both in the applying and withdrawing operations, and when placed in the neck or mouth of the bottle or tube will effectively close the same against 70 dust, bacteria or other contamination from outside sources, yet permits steam, vapors or air to pass through to the extent desirable in laboratory and hospital practices.

By forming the plugs in substantially the 75 manner shown, plugs of a few given sizes are adaptable to tubes or bottles having necks or openings varying in diameters.

Having thus described my invention, I 80 claim:

1. The process of making stoppers, consisting of subjecting an end of a cylindrical porous body to moisture and tapering of body toward the moistened end.

2. The process of making stoppers, consisting of subjecting an end of porous roll to moisture and tapering the roll toward the moistened end.

3. The process of making stoppers, consisting of subjecting an end of a porous pulp body to moisture and tapering the body toward the moistened end.

4. The process of making stoppers, consisting of subjecting an end of a porous body to moisture and compressing the same in a 95 tapered mold until shaped or "set".

5. The process of making stoppers, consisting of rolling a porous sheet into cylindrical form, moistening one end of the cylinder and inserting the moistened end into a 100 form or mold of smaller diameter than the cylinder.

In testimony whereof I affix my signature.

JEAN BROADHURST.
